UNITED STATES PATENT OFFICE.

ALFRED L. FREDEN, OF BROOKLYN, NEW YORK, ASSIGNOR TO LISTERATED GUM CORPORATION, OF NEW YORK, N. Y., A CORPORATION OF MAINE

DESIGN FOR A STATUETTE OR SIMILAR ARTICLE.

Application filed January 9, 1924. Serial No. 8,288. Term of patent 7 years.

To all whom it may concern:

Be it known that I, ALFRED L. FREDEN, a citizen of the United States of America, and a resident of Brooklyn, Kings County, New York, have invented a new, original, and ornamental Design for a Statuette or Similar Article, of which the following is a specification, reference being had to the accompanying drawing, forming a part thereof, and in which is shown a front perspective view of a statuette embodying my design.

I claim:

The ornamental design for a statuette or similar article, as shown.

ALFRED L. FREDEN.
